UNITED STATES PATENT OFFICE

2,656,931

PACKAGING ARTICLE

Melbourne A. Beckmann, Cincinnati, Ohio, assignor to Aluminum Industries, Inc., Cincinnati, Ohio, a corporation of Ohio

Application August 17, 1949, Serial No. 110,815

2 Claims. (Cl. 211—60)

1

This invention relates to packaging articles such as valve tappets, including the tappet rods, and which might be broadly described as articles consisting of stems and an annular laterally projecting flange at the ends of the stems. Within this same category may be included certain types of bullets and shells and a wide variety of machined parts.

In my earlier Patent No. 2,457,197, dated December 28, 1948, I have described and claimed a dispensing holder for articles of the class set forth above. Reference is hereby made to said earlier patent.

It is an object of the present invention to provide a dispensing holder for articles of the class set forth which will have all the advantages of the structure of my earlier patent, but which will be less expensive to manufacture and which will use less material.

This and other objects of my invention which will appear as the description proceeds, or which will be pointed out specifically hereinafter, I accomplish by that certain construction and arrangement of parts of which I shall now describe an exemplary embodiment.

Reference is made to the drawings forming a part hereof and in which:

Figure 1 is a plan view of a blank from which an end wall support is made;

Figure 2 is an elevational view of the completed end wall support;

Figure 3 is a cross-sectional view taken on the line 3—3 of Figure 4 showing a pair of end wall supports with a plurality of valves supported thereon;

Figure 4 is a detailed cross-sectional view on an enlarged scale taken on the line 4—4 of Figure 3;

Figure 5 is a perspective view of a shipping container, parts being broken away to show how the holders are inserted, and

Figure 6 is a perspective view of a pair of end supports constituting a dispensing holder with only two valves remaining, showing that the holder still retains its set up condition.

According to the present invention the end support members are constituted of rectangular blanks of a stiff, relatively thick material, such, for example, as corrugated paperboard. Such a blank is indicated at 10 in Figure 1. Longitudinally of the blank and spaced at equal distances from the center line thereof, there are provided the score lines 11 and 12.

The blank 10 is provided with a parallel series of slots, alternate ones of which are longer slots

2

and the remaining ones of which are shorter slots. The longer slots are indicated at 13 and the shorter slots are indicated at 14.

It will be observed that one end of each of the slots lies in a line parallel to an edge of the blank and spaced from the edge of the blank by a distance slightly greater than the radii of the annular, laterally extending flange portion of the valve or other article to be supported. The alternate slots 13 extend across the blank towards the other edge thereof and terminate in a line parallel to said other edge and spaced therefrom the same distance as mentioned above.

The remaining shorter slots 14 extend across the score line 12 and terminate substantially in the score line 11, which of course is parallel to the blank edges adjacent the center of the blank.

In setting up the end supports the blank is folded on the score lines 11 and 12, thereby coming into an isosceles triangular cross-section configuration having the side walls 15 and 16, and the top wall 17. The portions 15 and 16 are then secured together by stitching, by adhesive or by staples as indicated at 18.

In use, a pair of end supports such as shown in Figure 2, are placed parallel to each other as seen in Figures 3 to 6 inclusive with the portions 15 on the outside and with the portions 16 facing each other.

It will be observed that the arrangement of slots described above produces in the finished end support as shown in Figure 2, a series of slots 19 alternating with a series of grooves 20. In assembling the dispensing holder, as best seen in Figures 3 and 6, the two end supports are arranged with the slots 19 in one end support opposite the groove 20 in the other end support. The valves or other articles are then placed in the end supports as shown in Figures 3 to 6 inclusive, with the neck portion adjacent the valve head lying in the slot 19, with the tappet end of the valve stem lying in the groove 20. In this manner the valves are maintained separate from each other, so that nicking of one valve by contact with the other is obviated.

By virtue of the spacing of the end of the slots 13 from the carton edges, the edge of the annular extending portion of the valve head is raised above the supporting surface, as best seen in Figure 4, and if the slots 13 and 14 are spaced apart a distance slightly greater than the radii of the annular laterally extending flange portions, then the series of valve heads are kept out of contact with each other as best seen in Figure 3. Preferably the widths of the slots 13 and 14 as cut

50

in the blank 10 will be such that the valve stems will fit snugly therein, as by wedging. In this way the dispensing holder will be self-sustaining even with only two valves left in the holder, as best seen in Figure 6.

In packaging the holders filled with tappets, it is useful to provide containers such as indicated at 21 in Figure 5, which may hold any desired number of holder assemblies. These are packed in stacks with sheets 22 of board between each stack.

In use a single holder comprising the two end wall supports, together with the valves held therein, may be lifted out of the container 21 and placed upon a work table so that the individual valves may be withdrawn as required. Under such treatment the valves are not subject to scarring or nicking and they may be selected and withdrawn much more easily than from containers known before my earlier patent.

It will be observed that the dispensing holder and the end wall support, according to my present invention, contain all the advantages of the structure disclosed and claimed in my earlier patent above mentioned, while they use approximately 33% less paperboard, and while the series of manufacturing steps are considerably reduced. Thus, the entire blank of Figure 1 may be prepared in a single operation by cutting and scoring. It then requires only folding along the lines 11 and 12, and a securing together of the portions 15-16, as for example by stapling.

It will be understood that various minor modifications may be made without departing from the spirit of my invention, and therefore I do not intend to limit myself other than as set forth in the claims attached hereto, and as required by my earlier patent.

Having now fully described my invention, what I claim as new and desire to secure by Letters Patent is:

1. An end wall support constituting part of a

dispensing holder for articles consisting of stem portions with enlarged annular laterally extending flanged portions, said support being formed from a blank of rectangular form provided with a series of parallel transverse slots spaced from each other by an amount slightly greater than the radii of said flanged portions, all of said slots at one end terminating in a line parallel to a blank edge and spaced therefrom by a distance slightly greater than said radii, alternate ones of said slots terminating at their other ends in a line parallel to the other blank edge and spaced therefrom by the same distance, the remaining slots at their other ends terminating in a line parallel to the blank edges, but disposed substantially centrally of said blank, said blank being doubled on itself substantially centrally thereof with said doubled portions secured together, whereby to provide alternate slots and grooves in said support.

2. The structure of claim 1, wherein said blank is provided with two spaced longitudinal score lines, and wherein said remaining slots extend across one of said score lines and terminate substantially in the other score line, said blank, when folded upon itself on said score lines, having substantially an isosceles triangular cross-section.

MELBOURNE A. BECKMANN.
